DESIGN FOR A CIGARETTE CASE

Malcolm A. Vendig, Sands Point, Long Island,
N. Y.

Application May 22, 1940, Serial No. 92,516

Term of patent 7 years

To all whom it may concern:

Be it known that I, Malcolm A. Vendig, a citizen of the United States and residing at Barkers Point Road, Sands Point, Long Island, in the county of Nassau and State of New York, have invented a new, original, and ornamental Design for a Cigarette Case, of which the following is a specification, reference being had to the accompanying drawing, forming part thereof.

I claim:

The ornamental design for a cigarette case, substantially as shown.

MALCOLM A. VENDIG.
